TAPPET

Edwin J. Fisk, Cleveland, Ohio

Application July 18, 1935, Serial No. 32,049

8 Claims. (Cl. 123—90)

The principal object of this invention is to provide a device adapted to serve as an interponent between spaced reciprocating parts, which interponent will automatically change in length to 5 compensate both for shrinkage and elongation of the space in which it is adapted to operate.

A specific object is to provide an improved automatically adjustable valve tappet, and more specifically one that operates mechanically, as 10 distinguished from hydraulically, pneumatically, etc. Such a device has a present need in that it will, for example, permit tappets to be placed in an engine without requiring any initial adjustment.

15 A further object is to provide, in connection with a valve operating mechanism, means for insuring that the valve stem and tappet will remain in contact at all times, although unconnected, and irrespective of the provision of operating clearance, so that the resulting impact noise, as this 20 space is taken up in opening the valve, will be less noticeable by reason of occurring in an enclosed part of the engine ordinarily supplied with sufficient lubricant, as fluid or mist to dampen 25 the noise.

A further object is to reduce valve surge in an internal combustion engine.

Other objects and features of the invention will 30 become apparent from the following description relating to the accompanying drawing, showing preferred embodiments.

In the drawing, Fig. 1 is a sectional view of an internal combustion engine valve mechanism assembly, including an embodiment of my invention 35 in the form of a tappet; Figs. 2 to 4 are sectional views, taken as indicated at 2—2 on Fig. 1, showing one form of tappet in various illustrative operating positions of its parts; Figs. 5 and 6 are transverse sectional views, as indicated at 5—5 40 and 6—6 respectively on Fig. 1; Fig. 7 is a central longitudinal sectional view of a modified form of tappet; Fig. 8 is a side elevation of an 45 adjusting cam (one of the tappet parts of Figs. 1 and 7), and Fig. 9 is a sectional view corresponding to Fig. 2, showing still another modified form of tappet.

As embodied in a valve tappet or push rod, the illustration (Fig. 1) shows the tappet assembly 1 adapted to operate in a suitable smooth bore B in the engine block or a bracket thereon. The lower end of the assembly 1 is adapted to 50 engage an operating cam C or other valve operating means and the upper end is arranged to engage the lower end of the valve stem v in a manner to successively unseat and release the

valve V which latter is closed or seated by the usual spring S, as the cam rotates in contact with the tappet,—all as is well known. The spring S in automobile engines, usually exerts from between fifty to eighty pounds pressure, 5 applied as against a "washer" W, e. g. tending to close the valve.

A predetermined operating clearance of from .006" to .008" is ordinarily provided, and this occurs between the top of the tappet and the 10 bottom end of the valve stem, so as to enable full seating of the valve when the valve stem and tappet are lengthened, as by increased engine heat. This clearance has to be set with great care, for if the clearance is too small, then full seating will 15 not obtain under high temperature conditions, and if too great, the engine becomes noisy in operation, and the valves do not open to the extent they should. The illustrated embodiments, (see first Figs. 2 to 4) effects the necessary take-up when the space between the valve stem and the cam e. g. contracts—as when the engine is hot—and the necessary expansion to compensate for shortening of the stem and tappet—on cooling 20 e. g.—, as will now be shown.

The main tappet body comprises an elongated cylindrical block of suitable metal 5, having an appropriately hard, lower face 6 adapted to ride on the cam. The body slides freely in the cylindrical bore of a sleeve 7, which fits snugly in the bore B forming the tappet guide. To secure the desired friction between the guide and sleeve, the latter may be made to have a "push fit" in the 25 guide or may, for further example, be appropriately split, so that it may expand in the guide. If the sleeve is split for its whole length, this 30 may be done longitudinally (see 7a) at one side only (as illustrated) or it may be split at various places for part of its length either longitudinally or diagonally or in any other fashion that may be 35 found effective.

Any other known or suitable expedient may 40 be used to insure that the sleeve 7 will move less readily in its bore than does the body 5 in the bore of the sleeve. I prefer to utilize this differential in effecting the automatic adjustment, as will be later shown.

Near its upper end the body 5 has a central bore 8 adapted to freely slidably receive a plug 10 of suitable material, preferably operatively 45 identical with that of the valve stem.

The body 5 also has a transverse slot 12 for receiving the adjusting cam or cams and this slot may extend to the top of the body (as shown). The planar side and bottom surfaces of the slot 55

indicated at 13 and 14 are accurately finished to respectively support and embrace a cam member 15, which moves freely in the slot and has an upper cam surface 15a engaging the lower end surface 10a of the plug 10 (or the lower end of the valve stem, as desired), and a lower cam surface 15b adapted to ride on the planar bottom surface 14 of the slot. The cam may be maintained in position in the block 5 for vertical floating movement in the slot 12 by a cross-pin 17 formed thereon or disposed in a transverse bore of the cam, the ends of the pin extending laterally from the cam into accurately fitting sliding contact with respective slots 19, positioned transversely 15 of the slot 12 and extending beyond the upper and lowermost operative positions of the cross pin. The slots 19 (as shown) are open at the top of the body.

To operate the cam by relative movement of the body and sleeve a portion of the cam is formed into an arm 16 which may have a cylindrical head 20 adapted to fit into a lateral guideway 21 in the wall of the sleeve 7. As shown, the wall protrudes inwardly somewhat to radially amplify the guiding surfaces and permit a considerable angular movement of the cam arm without disengaging the head from its guide. This inwardly protruding portion of the wall of the sleeve 7 may be formed as a punching operation, thus affording the necessary surface amplification and finish to suitably fit the cylindrical head of the cam arm. Appropriate clearance is provided at 22 for the inwardly protruding portion of the sleeve when the parts are in the relative position shown in Fig. 4 e. g.

The connection between the cam arm and sleeve may, of course, comprise a cross-pin in the sleeve and a yoke formation in the end of the arm, (not illustrated).

It is obvious that as the body 5 moves with relation to the sleeve, the effective tappet length is increased or diminished, depending on which way the cam is rotated.

As shown in Figs. 2 to 4, the movement of the body 5, with reference to the sleeve 7, in a downward direction, is resisted by a suitable compression spring 25 which is interposed between the upper end of the sleeve 7 and a suitable shoulder, formed as by a split ring 26, seated in a groove 50 27 in the top portion of the body 5.

An illustrative cam shape is shown in Fig. 8, wherein it will be noted that the lower curve surface 15b is formed as an arc generated about a point 15c lying eccentric to the axis of the cross-pin 17 on one side and the upper curve surface 15a is generated as an arc struck about the point 15c' offset from the axis of the pin on the opposite side from said axis, projections of the arcs being indicated by broken lines at 15d and 15d'. Alternatively the cam curve may be generated as an involute suggested by the broken line beginning say where the line 15d intercepts the horizontal axis of the cam. The cam surface may be altered to suit practical conditions, and as shown, is developed to produce as much as $1/8$ " variation in the effective length of the tappet, which, in actual practice at the present time, would not be necessary.

The modification illustrated in Fig. 7 is only 70 with reference to the manner in which the spring 25 is secured at its upper end. Otherwise, the figure shows the previously described tappet in longitudinal central section, the plane of which it is at right angles to that of Fig. 2. Since the 75 plug 10 bears upwardly at all times on the valve

stem, this may be provided with a suitable rigid head, as at 10d, and overhanging flange 10e abutted by the spring. Thus the opposite end of the spring constantly tends to urge the sleeve downwardly and to rotate the cam in a manner to 5 relatively elongate the tappet assembly.

Referring to the modification shown in Fig. 9, it will be noted that the body member 5, lying within the sleeve 7, has a reduced portion or stem 30 extending below the cam-carrying slot, and that the sleeve has its wall partially in spaced relation to the stem and is provided below said space with an inwardly extending flange 31, having a central opening in sliding contact with the stem. This provides a space inside the tappet assembly for a spring 25' which is in operative effect identical with the spring 25.

It will be further noted that the wall of the sleeve 7' is made considerably thicker than the wall of the sleeve 7, previously described, thus affording adequate radial bearing surfaces for the head 20' of the cam 15'. The cam 15' in this instance is shown as comprising two operatively identical parts which may, as above mentioned, be made so that one straddles the other or which may be disposed side by side. The lower end of the valve stem v rests, as shown, directly on the upper cam surfaces.

If it is desired to amplify the valve-operating cam-contacting surface of the lower end of the body, any suitable arrangement of the head for the stem 30 may be provided. Preferably a head member 35 is attached to the lower end of the stem, the head having the desired chilled bottom surface (if cast iron) or being otherwise made suitably hard for engagement with the cam. The head has a socket on its top side for receiving the stem 30, and preferably the stem 30 is made oversized and is attached by being packed in frozen carbon dioxide or other suitable chemical to reduce its diameter to an extent such that it will easily slip into the socket of the head. Thereafter, under operating temperatures the joint between the stem 30 and head 35 will be sufficiently tight so that there is no possibility of the head coming loose in service. This feature is obviously applicable to conventional mushroom type tappets.

The head 35 in the position thereof shown, prevents disassembly of the tappet because the body may not be moved upwardly far enough with respect to the sleeve to permit disengagement of the cam heads 20' from their guiding slots in the side walls of the sleeve 7'.

The manner of assembling the tappet in the form shown in Fig. 2, for example, may be best understood from reference to Fig. 4. Assuming that the spring 25 and its retaining ring 26 has not been attached to the body, the body is inserted upwardly into the sleeve 7, and then, with the sleeve and body in the relative position shown in Fig. 2 or 3, the cam or cams may be lowered into position in the slots 12 and 19 until the head or heads 20 are horizontally opposite the guide slot or slots 21, whereupon the head is, or heads are, swung outwardly into engagement therewith by further lowering of the cam or cams. Thereafter the spring 25 is slipped over the top of the body and the slit ring 26 expanded and seated in its groove. The tappet remains in assembled condition during shipment without special attention, other than to provide for retaining the separate plug 10 (when used) in place in its bore. At such times the spring holds the body 75

and sleeve relatively extended—about as shown in Fig. 4.

The operation is as follows:

Assuming that the valve is closed (see Figs. 1 and 2) and that the operating cam C is about to raise the tappet to open the valve. It will be seen that during the preceding "rest" period the spring 25 will have acted through the cam 15 to take up all clearance and hold the tappet longitudinally expanded to fill all the space between the valve stem and cam. The spring does this whether its reactions are taken up by the body 5 or by the valve stem (through the plug 10 e. g. as in Fig. 7). The spring action is merely one of shoving the sleeve down to turn the cam 15 counter-clockwise, and this accomplishment requires very little spring strength on account of the mechanical advantage afforded by the cam arm and cam.

20 As the high point of the valve operating cam C now operates to raise the tappet assembly and valve, the cam 15 is definitely locked against turning, partly by reason of the close proximity of the respective loci of the cam axes to the tappet axis, and partly by reason of the frictional force (braking action) of the surfaces 14 and 10a of the body and plug respectively bearing on the cam with the full force of the valve spring S.

25

As the high point of the cam C passes the tappet axis the travel of the tappet is reversed, but the valve spring continues to maintain braking pressure on the cam 15, the same as it did during upward travel of the valve, and therefore (except as hereinafter pointed out) the acquired 35 length of the tappet remains the same.

Now, assuming that there has been an alteration in the length of the valve and tappet assembly by which the stem becomes in effect too short (as by expansion of the engine block relative to the valve and tappet assembly and/or by reason of wear between the cam and tappet), the spring will again act after the concentric or low surfaces of the cam C are adjacent (but not in contact with) the lower end of the tappet body, to elongate the tappet and take up all play and thereafter the "acquired length" will be positively held as already described.

Now, assuming that wear has occurred between the valve and valve seat or that the valve stem or tappet is expanded by heat and the tappet assembly thereby becomes in effect too long, it will be seen that this must be compensated for or the valve cannot properly seat, and the valve seat surfaces will become unserviceable ("burned"). The tappet in such case automatically "shrinks" in length as follows:

Assuming the cam is operating at high speed, as during normal running speed of the engine, the valve is actually kicked, not gradually lifted to open position. This normally either throws the valve stem out of contact with the tappet or the tappet out of contact with the cam and breaking pressure on the adjusting cam 15 is momentarily relieved at a time when the valve commences to close. The valve spring, however, acts through the valve stem and parts 10 and 15 to move the tappet body toward the cam C. At such time the drag of the sleeve 7 in its guide operates to turn the cam 15 clockwise a slight amount, shortening the tappet. Now, if on full seating of the valve there is no clearance to take up, the tappet will remain in effect shortened by said action of frictional drag just mentioned.

75 A feature of the invention that is of general

utility in valve tappets irrespective of whether or not automatic adjusting means is present is the "snubbing" action of the outer wall surface of the tappet on the guide bore. This when used in connection with a tappet of conventional construction maintains the effective upper end of the tappet in contact with the lower end of the valve stem at all times, so that (in the event of clearance) the noise occurring when the play is taken up as at the beginning of the valve lifting stroke of the valve operating cam, will be damped because of occurring in an enclosed and oil bathed part of the engine, namely the cam and cam shaft housing.

Such snubbing is also effective in reducing what is known as valve "surge" or flutter. Valves in existing engines have a tendency to rebound from their seats on account of closing at extremely high velocity, unrestricted by any detaining force beyond the slight friction of the valve and tappet guide walls on the respective parts guided thereby. The braking action of the tappet on its guide wall (whether secured by expansion as of a split sleeve or original push fit of the sleeve in the guide bore) reduces this valve flutter, rebound or surge to an appreciable extent.

I claim:

1. A clearance take-up device comprising two members and respective means slidably guiding them for movement parallel to each other, means to cause one of the members to slide less freely in its guiding means than does the other in its guiding means, and means operatively connected with both said members and reacting to change the effective length of the device consequent upon lagging of the less freely slidable member relative to the other member. 30 35

2. In an internal combustion engine having a valve and operating means therefor, a tappet comprising a body and a sleeve in which the body slides, said sleeve being slidable in a suitable guide on the engine, frictional means for causing the sleeve to lag behind the body, adjusting means actuated by the lagging movement of the sleeve to decrease the effective length of the tappet, during a portion of its operating cycle, and a spring acting on said adjusting means to increase said effective length during another portion of said cycle. 40 45 50

3. A clearance take-up device comprising two members and means guiding them for substantially synchronous normal movement, means to cause one of the members to move less freely than does the other, and means operatively connected with the less freely movable member, and moved thereby consequent upon lagging in movement of the less freely movable member relative to the other to change the effective length of the device. 55 60

4. In a valve mechanism, a tappet guide, a valve tappet comprising a body and a sleeve in which the body slides, said sleeve being also slidably in the tappet guide, frictional means between the sleeve and guide for causing the sleeve to lag behind the body, and means associated with the body and connected with the sleeve and actuated by the lagging movement of the sleeve, said means tending to increase the effective length of the tappet in one direction of movement thereof, and tending to decrease the effective length in movement in the opposite direction.

5. An adjustable length interponent for spaced parts, one of which is reciprocated by the other, 75

- comprising two telescoping elements, the outer of said elements being slidably mounted in a guide, the inner element being slidable in the outer element, the outer element having greater frictional resistance to sliding in its guide than the inner, and means operated by said frictional differential to change the effective length of the interponent at a predetermined portion of the reciprocating movement of the reciprocating part.
10. An adjustable length interponent for spaced parts, one of which is reciprocated by the other, comprising a sleeve having a guide, a body slid-able in the sleeve, said body having less resistance to sliding in the sleeve than does the sleeve in its guide, one of said parts operatively engaging the body, a cam carried on the body and having an arm connected with the sleeve so as to be operated by relative movement of the sleeve and body, the other of said parts operatively engaging the cam for movement, thereby longitudinally of the interponent, when the interponent is bodily moved to transmit reciprocating movement to the said reciprocated part.
15. 7. An adjustable length interponent for spaced

parts, one of which is reciprocated by the other, comprising a sleeve having a guide, a body slid-able in the sleeve, one of said parts operatively engaging the body, a cam carried on the body and having an arm connected with the sleeve, a spring bearing on the sleeve and acting to turn the cam through said arm, the other of said parts operatively engaging the cam for movement thereby longitudinally of the interponent when the interponent is bodily moved to transmit reciprocating movement to the reciprocated part.

8. A valve tappet comprising axially relatively movable parts and a cam operatively interposed between them and adapted to be turned to so move said parts for lengthwise adjustment of the tappet, an expandible sleeve forming a guide for one of said parts and adapted to operate in relatively tight frictional engagement with a tappet guide bore of an engine, said sleeve having an operating connection with said cam, said cam being rendered active to move said parts, as stated, consequent upon relative axial movement of the sleeve and the part guided thereby.

EDWIN J. FISK.
